UNITED STATES PATENT OFFICE.

WILLIS J. PEELLE, OF CHICAGO, ILLINOIS.

VACUUM CAPPING MACHINE.

Application filed September 15, 1921. Serial No. 500,724.

To all whom it may concern:

Be it known that I, WILLIS J. PEELLE, a citizen of the United States, residing at Chicago, in the county of Cook and State of Illinois, have invented certain new and useful Improvements in Vacuum Capping Machines, of which the following is a specification.

The invention relates to vacuum capping machines and more particularly to an automatic machine for sealing in a vacuum the caps or other closures upon glass jars, tumblers, bottles and the like, in continuous progressive operation.

In the art of preserving food stuffs and other perishable substances it is desirable to exhaust the air from the container after filling, and seal it in a vacuum for the protection of the contents. Commercial machines heretofore used for that purpose have been inadequate in that their processes are comparatively slow and require much manual manipulation in operation, some employing large tanks in which the containers are placed and the air content of the tank then exhausted, and requiring multiple means for sealing the containers when exhausted.

It is the principal object of this invention to provide a machine which automatically exhausts and seals individual containers in rapid succession without manual handling.

Another object is to provide a machine in which the containers are passed through the machine on a travelling carrier arranged to make intermittent pauses for the operation of the sealing devices.

A further object is to provide automatic means for forming a vacuum chamber about the container filling opening, the exhaustion of which requires the minimum displacement of air and enables rapid efficient operation in sealing the containers.

Another object is to provide automatic means in a machine of this character adapted to successively grasp and support a series of travelling containers during the sealing operation, and simultaneously effect an air seal about a portion of the container.

Other objects and advantages will be apparent in the following description of a

preferred embodiment of my invention, which I have illustrated in the accompanying drawings.

In the drawings, Figure 1 represents an end elevation of a complete machine. Fig. 2 represents a side elevation of the same machine. Fig. 3 represents a plan view of that portion of the machine lying below the horizontal plane of the line 3—3 in Fig. 1. Fig. 4 is a fragmentary sectional plan view of a portion of one side of the machine taken on the plane of the line 4—4 in Fig. 2. Fig. 5 is a fragmentary vertical section taken on the plane of the line 5—5 in Fig. 3. Fig. 6 is an enlarged sectional detail of the clamping and sealing members. Fig. 7 is an enlarged detail of the reverse side of the slide members illustrated in Fig. 1 and Fig. 8 is a horizontal section taken on the plane 70 of the line 8—8 in Fig. 1. Fig. 9 is a fragmentary sectional view taken substantially in the plane of line 9—9 of Fig. 8.

Stated generally, my invention as illustrated herein comprises a horizontal belt conveyor which is driven with regularly distanced intermittent pauses and is adapted to carry the containers standing thereon in upright position. A pair of side chains serve to retain the containers on the belt and have means for regularly spacing the containers. Midway of the conveyor belt a pair of resiliently lined clamping members are caused to successively embrace the passing containers and hold the latter at rest during the period of pause of the mechanism while an overhead reciprocating device is lowered in contact with the rings to form a vacuum chamber, whereupon automatic means associated with the reciprocating support for the latter device operates to exhaust the air from the chamber and the container, and a plunger seats the container cap in position to effect the closure of the latter. With the resumption of the operation of the machine 95 the containers are released and carried on to the discharge end of the conveyor. The containers may be placed on and taken off the conveyor by hand or by machine.

Obviously my invention may be incorporated in a variety of structural embodiments, and I desire it to be understood that the

form disclosed herein is merely for purposes of illustration, all legitimate variations and modifications of which I aim to cover in the subjoined claims.

5. More particularly described, the machine as illustrated comprises a main frame having upright skeleton side members 1 and 2 suitably cross connected as at 3. The side members are preferably formed with horizontal tables 4 and 5 on their upper portions. Upright bearing supports 6 and 7 also may be laterally mounted on the side members of the frame. Positioned at each end of the frame and adjacent to its upper surface are a pair of shafts 8 and 9 journaled in suitable bearings 10 and 11 secured to the end surfaces of the frame members. Each of the shafts carries a roller or belt pulley 12 and 13 upon which is mounted 10 a continuous conveyor belt 14, of any suitable material, the upper run of which is parallel to the horizontal upper surfaces of the frame. The bearing 10 for the shaft 8 may be constructed for horizontally adjusting the position of the shaft so that suitable tension may at all times be maintained on the conveyor belt.

15. The conveyor belt 14 is arranged to operate with intermittent progress, during the pauses of which the sealing operations are performed as hereinafter described. The intermittent propulsion of the conveyor may be accomplished by means of an interruptedly driven train of gears. In my present arrangement, the latter comprises a shaft 15 mounted transversely of the lower portion of the main frame, and carrying a pulley 16 which is driven by a belt 17 from a motor 18 suitably mounted on a lower cross member of the main frame. For convenience of illustration I have shown a simple belt connection for the primary power transmission which, however, in practice may include a jack shaft and speed reducing pulleys or reduction gears to reduce the speed of the mechanism driven thereby to a rate suitable to the particular requirements under operating conditions.

20. The shaft 15 extending through the side members of the frame carries at one end a cam member 19 having a generally circular periphery and a radially extending lobe 20 projecting therefrom. Operatively associated with the cam is a driven member 21 carried on a shaft 22 also journaled in the frame, and whose periphery is provided with a series of regularly spaced notches 23 suitably formed to receive the single lobe of the cam 19. The peripheral spaces between the notches are concavely curved to receive the circular portion of the cam periphery, and the latter is recessed at the sides of the cam lobe to permit the passage of those portions of the notched member immediately adjacent to the notches.

25. It will here be seen that in the operation of the cam member the driven member is intermittently advanced by engagement of the cam lobe, further revolution of the driven member being prevented by the interengagement of the circular periphery of the cam member with the inwardly curved portion of the driven member between the notches.

30. The driven member 21 has associated therewith in fixed relation a gear 24, both gear and driven member being loosely mounted on the shaft 22 and retained thereon against longitudinal displacement by any suitable means as by collar 25. The gear 24 is in driving engagement with a pinion 26 mounted on a stub shaft 27 journaled on the bearing support 7, and carrying at its other end a gear 28. The latter gear drives a pinion 29 rigidly mounted on the shaft 22. Fixed on the opposite end of the shaft 22 is a gear 30 which is in driving engagement with a gear 31 mounted on the shaft 32 journaled on the ends of the members of the main frame. The shaft 32 carries also a pinion 33 engaging the gear 34 fixed on the shaft 9 which carries the conveyor belt pulley 13.

35. In the operation of the train of gears just described it will be apparent that the conveyor belt will be advanced only during engagement of the cam lobe 20 with the driven member 21, and that during the balance of the rotation of the cam the conveyor belt will be at rest. The distance and frequency of the progressive movement of the conveyor may be arranged at any desired proportion by changing the relative diameters of the cam member and its driven member and the number of notches in the latter.

40. Side guiding chains 35 and 36 are designed to pass along the upper face of the conveyor belt adjacent to its outer edges, serving to retain the containers being carried by the conveyor, and also to regularly space and aid in propelling the containers on the belt. The latter purpose may be accomplished by means of regularly spaced projecting teeth 37 carried by the chains 110 and projecting inwardly over the conveyor.

45. The guide chains 35 and 36 are operatively supported at each end by sprockets 38 to 41 mounted on vertical spindles journaled in the upper portion of the main frame. One each of the two sprockets supporting each of the chains is power driven. A bevelled gear 42 mounted on the lower end of the spindle carrying the sprocket 38 is in driven engagement with a bevelled gear 43 splined on the shaft 22, the latter gear having suitable means for securing it in longitudinally adjusted position on the shaft.

50. In order to accommodate containers of

different dimensions it is desirable to adjust or vary the distance between the guide chains 35 and 36 and for this purpose I have provided adjustable mountings for the 5 sprockets for both chains as illustrated in connection with chain 35 in Fig. 4. The spindles 44 and 44^a operate in bearing plates 45 which overlie horizontal extensions 46 formed on the upper portions of the frame 10 members 1 and 2. The plates 45 are slotted as at 47 through which latter binding bolts 48 are secured in the main frame. By this means the oppositely positioned sprockets may be moved transversely of the frame and 15 variously spaced.

The driven spindle 49 carrying the bevelled gear 42 is operatively connected with the oppositely positioned spindle 44. Each of the spindles 49 and 44 carries a pinion 20 50 and 51, which is in mesh with one of a pair of intermediate gears 52 and 53 journaled on pins carried in a pair of swinging arms 54 and 55 mounted on the respective sprocket spindles. The gears 52 and 53 are 25 secured in interengaging relation by means of a link 56 extending between the journal pins. It will here be seen that with the separation of the chain driving sprockets in the adjustment described, the intermediate 30 gears will be swung on the supporting arms 54 and 55 to compensate for the varied distance between the spindles and be constantly in mesh.

In my preferred arrangement of a mechanism for operating the clamping members, I 35 have mounted on each side of the central portion of the conveyor belt a pair of disks 57 and 58 rotatable on vertical journals 59 and 60 mounted on the upper horizontal 40 portions 5 and 4 of the main frame. The outer peripheries of the disks are formed with sprocket teeth to engage the links of the guide chains 35 and 36 and be rotated thereby. Each of the disks carries a series 45 of radially projecting members 61 which comprise the clamping members for securing the containers in position for the sealing operation, and which also form a portion of the vacuum chamber. The members 61 are 50 preferably formed as half rings projecting beyond the peripheries of the disks and having their bases extended for support on the disks. The clamping members are positioned on the disks so that with the rotation 55 of the latter they meet in opposition above the conveyor belt and together form an enclosing ring adapted to embrace the container (see 62 in Fig. 1) as near the mouth of the latter as its contour will permit. 60 The contacting surfaces of the clamping members are faced with a resilient lining 63, preferably rubber, which is adapted to effect an air-tight seal between the oppositely contacting clamping members and the container embraced therebetween. Each of the 65

clamping members is mounted on a vertical stem 64 (see Fig. 5) secured in suitable bearing bushings 65 rotatably mounted in the disk, the latter carrying at its lower end a cross arm 66 (see Fig. 4) which is fixed centrally upon the bushing. The cross arm carries a roller 67 at one end thereof, and to the other end of the arm is attached a tension spring 68 having fixed attachment at its other end upon a collar 69 formed integral with the disk 58 and rotating therewith.

Positioned beneath each of the disks and serving as supports for the journals 59 and 60 upon which the disks operate, is a bearing plate 70 adjustably secured to the upper horizontal portions of the main frame. That portion of the bearing plate immediately underlying the disk is recessed as at 71, and the internal faces of the side walls of the recess form a cam upon which the rollers 67 are held in travelling contact by the tension springs 68. The contour of the cam periphery is such that through the operation of the roller arms 66 over the lobe 72 each of the clamping members as it approaches the conveyor belt is swung in advance of the travel of the disk so that the openings adapted to receive the containers 75 approach each other squarely as represented in the dotted figures 73 and 74 (Fig. 3). Likewise when the clamping members release the containers they are separated through the operation of the cam means in like relation. This provision prevents the striking of the containers with the corners of the clamping members and also permits the latter to close about the containers evenly and to effect contact thereabout simultaneously. In accommodating different sizes of containers, the clamping members 61 may be replaced by those of different dimensions, and the adjustment of the relative spacing of the disks 57 and 58 may be accomplished by the transverse movement of the adjustable supporting bearing plates 70 which, as illustrated in Fig. 4, are constructed with slots 75 through which the bolts 76 extend for securing the bearing plate to the upper member of the main frame. By this means also the guide chains 35 and 36 may be kept in alinement with the axis of the travel of the conveyor belt by the like adjustment of the disks and the 115 sprockets.

The overhead sealing mechanism is supported by a pair of upright standards 77 and 78 mounted laterally on the upper portions 4 and 5 of the main frame. The standards carry at their upper ends a crank shaft 79 journalled in the standards with the crank positioned therebetween. One end of the crank shaft extends outwardly to support a sprocket 80 which is driven by a sprocket chain 81 operating also on a driv- 120 125 130

ing sprocket 82 carried on the shaft 83 transversely journaled on the main frame. The shaft 83 also carries a sprocket 84 which is driven by a chain 85 running to the sprocket 86 carried on the shaft 15 and receiving power therefrom for the operation of the crank shaft 79. It will be noted that the connections are such that the crank shaft 79 is in continuous operation while all of the other mechanism hereinbefore described is intermittently at rest.

Carried on the inner surfaces of the upright portions of the standards 77 and 78 are a pair of slideways (see Fig. 8), that on one side being of the ordinary slotted rail construction illustrated at 87. The other of said slides comprises a plate 88 secured to the inner side of the standard 78 and having an undercut tongue extending inwardly to receive the slide block 89 which may be adjustably secured thereto in any vertical position by means of the hand lever 90 having an eccentric pin extending into the slide member 91 and adapted thereby to lock the slide bar 89 in relation to the block 88. The slide block 89 carries a slotted rail portion on its inner side between which and the opposite slide rail 87 is positioned a reciprocating cross head 92 carrying a pair of upwardly extending lugs 93. Between the two lugs is pivoted one end of a connecting rod 94 which has a bearing at the other end upon the crank throw in the crank shaft 79. The connecting rod 94 is constructed with a turn buckle 95 by means of which the length of the rod may be varied to adjust the relative position of the range of movement of the cross head 92.

Supported in the lower end of the cross head (see Fig. 6) is a tubular stem 96 extending downwardly therefrom and carrying at its lower end a rigid plate or disk 97. Mounted also upon the tubular stem is a cup-shaped member 98 through the wall of which the stem slidably extends, the lower portion of the cup extending beyond the plate 97 and carrying at its lower edge a resilient gasket 99 preferably of rubber. The cup-shaped member 98 is constructed to provide a stuffing box comprising the cap 100 screw-threaded upon the upper extension 101 of the cup member and providing space therebetween for suitable packing material 102 for maintaining air-tight contact between the cup-shaped member and the stem 96 upon which it slides. The cup-shaped member is urged downwardly into abutment with the end plate 97 by means of a compression spring 103 having its upper abutment against the lock nut 104, which secures the hollow stem 96 in the lower portion of the cross head.

As each container is embraced between the opposing pair of clamping members 61 the conveying mechanism is interrupted in

its operation, and the container held at rest while with continuous operation of the crank shaft 79 the cross head 92 is operated to lower the stem 96 so that the cup-shaped member 98 descends upon the upper surface of the clamping rings 61, the resilient gasket 99 engaging with the upper surfaces of the clamping rings and being compressed thereagainst with the further descent of the cross head by means of the compression spring 103 to form a completely enclosed air-tight chamber about the upper end of the mouth of the container 62.

Upon the complete sealing of a vacuum chamber as thus described, I have provided means for exhausting the air from the chamber and consequently from the container through the passage 105 in the tubular stem 96. This passage extends upwardly through the cross head (see Figs. 1 and 7) and connects with a lateral passage 106 extending to the side of the cross head and opening through the face of the sliding surface. Formed in the slide block 89 is a port 107 opening also through the surface of the slideway and with which is connected a pipe 108 leading through the valve 109 and thence to a suitable vacuum pump (not shown). The valve 109 is arranged to be operated by means of the tripping arms 110 and 111 rigidly mounted in the cross head and so positioned as to engage in the reciprocation of the cross head above and below the operating arm 112 fixed on the stem of the valve.

The air passages and valves are so arranged that with the completion of the sealing of the members forming the vacuum chamber the passage 106 is in register with the port 107, and at the moment of sealing venting ports 109^a and 109^b of the valve 109 are connected so that the air within the chamber is immediately exhausted.

The further downward progress of the cross head and the stem 96 carries the plate 97 into contact with the cap or cover 113 (which has been previously loosely positioned on the container) at the moment when the exhaustion of the chamber is complete and forces the cover into sealing contact with the container. The seal may be facilitated by the employment of a gasket 114 of suitable material, as of rubber, placed between the edges of the mouth of the container and the cover.

At the end of the downward stroke of the plate 97 the valve 109 is further operated to close the vacuum pump line and admit outside air to the port 107 and the passages leading to the vacuum chamber, thereby restoring atmospheric pressure within the chamber. The cross head 92 then begins its upward movement which raises the plate 97 from the cover of the container and in succession the cup-shaped

member 98 is released from the clamping rings. Whereupon the conveyor mechanism is again put in operation, the clamping members are separated and the container conveyed to the discharge end of the machine.

In order to accommodate containers of varying height, it is, of course, necessary to adjust the range of movement of the cross head 92 and the mechanism suspended therefrom. This may be accomplished by means of the adjustable connecting rod 94. In order also to adjust the position of the exhaust port 107 in relation to the changed range of movement of the cooperating passages in the cross head, the slide block 89 may be raised or lowered as required, as previously described, so that the timing of the exhaustion of the chamber and the subsequent admission of atmospheric pressure may be accurately secured.

It will now be apparent that I have provided a machine for sealing in a vacuum, jars or other containers customarily employed in preserving perishable substances, which is particularly adapted to the rapid efficient and economical commercial accomplishment of the purposes set forth.

I claim as my invention:

1. In a machine of the class described, an intermittently operated conveyor adapted to carry a series of containers to be sealed, a plurality of clamping members operable in pairs to successively embrace said containers and form a lateral seal thereabout, a reciprocable sealing head adapted to engage said clamping members and form therewith a sealed chamber enclosing the mouth of said container means associated with said sealing head through which to exhaust said sealed chamber and container, and means for sealing a closure on said container.

2. In an automatic vacuum sealing machine, a conveyor adapted to carry a series of non-yielding containers having loosely placed closures, a pair of movable supports positioned on opposite sides of said conveyor, a plurality of half ring clamping members mounted on said supports respectively, said members being adapted in the operation of said supports to meet in pairs and to yieldably embrace successive containers, means for causing the intermittent operation of said conveyor and supports, and a reciprocable sealing head adapted to successively engage said closures upon said containers while said conveyor and said supports are at rest and to coat with said clamping members to form a sealing chamber about said containers successively.

3. In an automatic vacuum sealing machine, means for propelling a plurality of non-yielding containers in spaced series, a pair of rotating supports positioned on opposite sides of the path of said containers,

each of said supports having a clamping member, said members being adapted to cooperatively clamp successive containers, and means coacting with said clamping members to form a sealing chamber about the successive containers while so clamped.

4. In a machine of the class described, a pair of laterally spaced travelling guides having opposed projections adapted to regularly position and propel a series of containers to be sealed, and a plurality of laterally disposed clamping members, said clamping members being arranged to move in pairs into opposed position about successive containers to secure the same, and means coacting with said clamping members to form a sealing chamber about the successive containers.

5. In a machine of the class described, a conveyor adapted to carry a series of containers to be sealed, a pair of laterally disposed travelling guides having means for regularly spacing said containers on said conveyor, a plurality of clamping members operable to successively embrace said containers and form a lateral seal thereabout, said conveyor, guides and clamping members being operatively arranged to pause as each container is so embraced, a reciprocable sealing head adapted to successively engage said clamping members during said pauses and form therewith a sealed chamber enclosing the mouth of a container, and means associated with said sealing head through which to exhaust and seal said container.

6. In a vacuum sealing machine, a conveyor adapted to carry a series of non-yielding containers to be sealed, laterally disposed groups of rotatably mounted clamping members operable across said conveyor in opposed pairs to successively embrace and secure said containers, and means coacting with said clamping members to form a closed chamber in which to seal a closure upon said containers while so secured.

7. In a machine of the class described, means for clamping a container, a reciprocal sealing head operable with said clamping means to effect a sealed chamber about the mouth of said container, automatic means through which the air may be exhausted from said chamber and container, and automatic means for seating a closure upon said container, said exhausting means being automatically operable to restore atmospheric pressure within said chamber when said closure is seated.

8. In a machine for vacuum sealing glass receptacles, a pair of horizontally arranged disks disposed in laterally opposite relation to a series of moving containers, a plurality of clamping members spaced about the periphery of each of said disks, said disks being rotatable in unison with the progress

of said containers, means for moving said clamping members relative to the disks to cause them to cooperate in opposite pairs to form a clamping ring about the successive 5 containers, and means coacting with said members to form a sealing chamber about said containers while so clamped.

9. In a vacuum sealing machine, a pair 10 of endless travelling guides operating in the same plane and adapted to propel a series of spaced containers, a pair of pivoted disks oppositely positioned in relation to said containers and having driven engagement with said travelling guides, and clamping members 15 on the disks adapted to successively clamp said containers in position to be sealed while forming a seal thereabout.

10. A vacuum sealing machine comprising, in combination, a pair of endless flexible 20 members operating in the same plane with portions in spaced parallel relation and adapted to move a series of containers in a rectilinear path and in spaced relation, a sealing means arranged to operate upon the 25 respective containers when the latter are moved into a predetermined position by said moving means, and means for holding the containers in such predetermined position comprising a pair of rotary elements mounted 30 for lateral adjustment with respect to the container-moving means.

11. In a machine of the class described, a pair of clamping devices adapted to successively clamp a series of moving containers, 35 each of said devices comprising a rotating element having a plurality of clamping members adapted to cooperate with the clamping members of the other device, a rotatable stem supporting each of said clamping 40 members and journaled in said element, a rocker arm fixed on each of said stems, a stationary support for said disk having a recess positioned substantially concentric therewith, said recess being adapted to receive 45 said rocker arms with one end thereof in operative contact with the inner wall of said recess, and tension means tending to maintain such contact, the inner walls of said recess being arranged with a contour 50 forming a cam operatively controlling the position of said rocker arms and thereby periodically swinging said clamping members in and out of radial relation to said element.

12. In a machine of the class described, a pair of clamping members adapted to receive and hold a container at intermittent periods, a pair of upright standards, a crank shaft mounted in said standards, a cross-head 60 having slidable support on said standards and actuated by said crank shaft, a sealing head mounted on said cross-head adapted to cooperate in lowered position with said clamping members to form a sealed 65 chamber about a portion of said container,

and means through which the air may be exhausted from said chamber.

13. In a machine of the class described, clamping means for effecting a lateral seal about a container, a reciprocating stem operable to approach said clamping means, a resiliently supported cup-shaped member having its base slidably supported on said stem and having a resilient edge adapted to engage said clamping means to effect a sealed 70 chamber about the mouth of said container, means through which the air may be exhausted from said chamber and container, and a plunger fixed on said stem within said cup-shaped member adapted to be advanced by said stem to forcibly seat a closure upon said container while so exhausted. 75

14. In a machine of the class described, a pair of standards, slideways on said standards, a reciprocating cross-head supported 80 in said slideways, a tubular stem on said cross-head, a cup-shaped member mounted on said stem adapted to complete a sealed enclosure about a portion of a container to permit exhaustion of the air therefrom, a 85 passage in said cross-head communicating with said tubular stem and having a port opening upon one of said slideways, and a cooperating port in said slideway adapted to communicate with a vacuum pump, said 90 ports being arranged to periodically register during the reciprocation of said cross-head and establish open communication between said sealed enclosure and said 95 vacuum pump.

15. In a machine of the class described, a pair of standards having slideways, a reciprocating cross-head supported in said 100 slideways, a tubular stem on said cross-head, a cup-shaped member mounted on said 105 stem adapted to complete a sealed enclosure about a portion of a container to permit exhaustion of the air therefrom, a passage in said cross-head communicating with said tubular stem and having a port opening 110 upon one of said slideways, a cooperating port in said slideway adapted to periodically register with said first mentioned port in the reciprocation of said cross-head, a connection adapted to lead from said last 115 mentioned port to a vacuum pump, a valve controlling said connection, and means on the cross-head for actuating said valve, said valve being operably arranged to alternatively connect said passages and sealed 120 enclosure with the vacuum pump and with the atmosphere.

16. In a machine of the class described, a frame supporting a pair of slideways, one of said slideways being longitudinally adjustable, a reciprocating member operable in said slideways, a crank shaft, a longitudinally adjustable driving connection between said crank shaft and said member, a 125 vacuum sealing head mounted on said member, a 130

ber, said member having a passage connected with said sealing head and opening upon said slideway, and a port in said adjustable slideway adapted to communicate with 5 vacuum pumping means and adapted to periodically register with said opening, said adjustable slideway permitting maintenance of a definite relation between said port and said opening in the various adjustable 10 ranges of movement of said reciprocating member.

17. A vacuum jar-sealing machine comprising, in combination, means for moving the jars longitudinally through the machine with a step-by-step motion, vacuum sealing means, and means for successively 15 clamping the jars and adapted to form in

association with said sealing means closed chambers around the jars.

18. A vacuum jar capping machine having 20 means for moving a series of jars longitudinally through the machine with a step-by-step motion, said means including a pair of elements rotating on spaced parallel axes, and means operatively associated with 25 said elements and operable as a jar is moved into position between the elements to form a ring encircling said jar, and means co-acting with said ring to form a closed 30 chamber.

In testimony whereof, I have hereunto set my hand.

WILLIS J. PEELLE.
